UNITED STATES PATENT OFFICE.

CHARLES ALBERT AND JOHN G. DINKELEBIHLER, OF CINCINNATI, OHIO.

ROTARY BRUSH.

SPECIFICATION forming part of Letters Patent No. 255,906, dated April 4, 1882.

Application filed September 27, 1881. (No model.)

To all whom it may concern:

Be it known that we, CHARLES ALBERT and JOHN G. DINKELEBIHLER, both of Cincinnati, Hamilton county, Ohio, have invented certain new and useful Improvements in Rotary Brushes, of which the following is a specification.

This invention relates to those devices which are more especially employed by barbers for removing dandruff from the human head; and the object of the first part of our improvements is to construct a brush capable of being readily operated and controlled by the barber's hands, as hereinafter more fully described, and pointed out in the claims.

The second part of our invention comprises a novel combination of ratchet-wheel, levers, pawls, connecting-rods, and a stop-pin, for the purpose of operating with a double motion the gearing of such hand-driven hair brushes, as hereinafter more fully described, and pointed out in the claims.

In the annexed drawings, Figure 1 is a side elevation of our machine. Fig. 2 is a rear elevation of the same, the metallic jacket of the brush-block being sectioned. Fig. 3 is an elevation of the ratchet-feed detached from the machine. Fig. 4 represents the preferred method of suspending our rotary brush.

30 A represents a light metallic frame, having at top a bar, *a*, for the convenient suspension of said frame, within which is journaled a driving-shaft, *B*, carrying the master-wheel *C* and ratchet-wheel *D*, the latter being operated by 35 the pawl *e* of lever *E*, that vibrates on said shaft *B*. This lever has a heel, *E'*, for a purpose that will presently appear, and is coupled to the operating-handle *F* by a link, *G*, said handle being pivoted at *f* to the frame *A*.

40 Furthermore, the handle is either bent at its lower end or has a loop, *F'*, to receive the operator's right fingers, while its curved upper end has attached to it at *f'* a connecting-rod, *H*, loaded at *h*, or else depressed with a spring 45 or equivalent device. This rod is coupled to a lever, *I*, vibrating on driving-shaft *B*, and carrying at one end a pawl, *i*, and at the other end a stop-pin, *i'*, projecting toward the ratchet-wheel *D*. Master-wheel *C* gears with a pinion, *J*, of shaft *j*, to which latter is secured a wheel, *K*, that drives the pinion *L* of fly-wheel shaft *M*. This shaft carries the fly-wheel *N* and a

grooved pulley, *O*, around which latter is passed the band *P*, that drives the grooved pulley *Q* of cylindrical brush-block *R*, this block being journaled in the lower part of frame *A*, as seen in Fig. 2. Block *R* is surrounded with a metallic casing, jacket, or shell, *S*, through which project the bristles *s*, which should either be composed of fine wire or 60 should have a number of such wires introduced among said bristles when the electrical attachment is used.

r r' represent fingers for conducting the electrical current into the jacket *S* from the metallic frame *A*, which current may be generated with any suitable magneto-machine, but preferably by two armatures, *T T'*, secured to a cross-bar, *m*, of shaft *M*, said armatures being adapted to revolve in close proximity to a 70 magnet, *U*. This magnet is attached to the frame *A* by an insulated bearing, *V*.

W is a screen of wire or perforated sheet metal for the purpose of preventing dandruff, &c., being thrown into the barber's face by 75 the centrifugal action of brush *s*.

X is a handle to be grasped by the barber's left hand, and Y is a loop to admit his right thumb.

Z is an elastic thong, band, or tube, having 80 its upper end attached to the ceiling of the barber-shop or other support, while its lower end is applied to the bar *a* of the brush-frame. (See Fig. 4.) A spring, however, may be substituted for this elastic support, the upper end 85 of the latter being adapted to travel on a fixed bar or rail, so as to render one brush available for a number of chairs in the shop.

Our machine is so suspended from the elastic support *Z* as to be elevated a slight distance above the head of the person occupying the barber's chair, thereby enabling the operator to control the implement with the greatest facility, which is done by grasping the handle *X* with the left hand, and then inserting 90 the thumb of the right hand in the loop *Y*, thus leaving the fingers of this hand at liberty to work the lever *F*. As this handle *F* is drawn toward the frame *A* it is evident the pawl *e* actuates the ratchet-wheel *D*, and thereby starts the train of gear-wheels, while the opposite swing of said handle causes the other pawl, *i*, to operate on said wheel *D*. The ratchet being thus operated with a double-le-

ver movement has considerable power imparted to it, and as a result of the peculiar arrangement of the train of gears a very high velocity is transmitted to the brush *s*, which 5 rotates in the direction of the arrow seen in Fig. 1, any dandruff thrown up by said brush being arrested by the screen *W*, which may have a small trough or receptacle at its lower edge to retain whatever particles may be projected against said screen. As soon as lever 10 *E* is brought to the position seen in Fig. 3 it comes in contact with the stop-pin *i'*, and is at once arrested, while the extreme opposite stroke of said lever is limited by its heel *E'* striking 15 against said pin.

We claim as our invention—

1. The combination, in a hand-driven rotary

brush, of frame *A*, fixed handle *X*, and loops *Y F'*, said loop *F'* being attached to the lever *F*, that actuates the gearing journaled in said 20 frame, substantially as herein described.

2. The combination, in a hand-driven rotary brush, of ratchet-wheel *D*, levers *E E' I*, pawls *e i*, actuating-rods *G H*, and pin *i'*, which pin projects from the heel of lever *I*, and serves 25 as a stop for the heel *E'* of the other lever, *E*, as herein described.

In testimony whereof we affix our signatures in presence of two witnesses.

CHARLES ALBERT.

JOHN G. DINKELBIHLER.
